United States Patent Office

Des. 176,415
Patented Dec. 20, 1955

176,415

SKI

Anton Heinrich Kaestle, Hohenems, Vorarlberg, Austria

Application May 20, 1953, Serial No. 25,113

Term of patent 14 years

(Cl. D34—14)

FIG. 1.

FIG. 1a

FIG. 2.

Figs. 1 and 1a are a composite top plan view of a ski, showing my new design; and

Fig. 2 is a side elevational view thereof.

I claim:

The ornamental design for a ski, as shown.
